United States Patent Office

Des. 185,933

Patented Aug. 18, 1959

185,933

DESK BASE FOR A WRITING INSTRUMENT

Walter Irion Bieger, Janesville, Wis., assignor to The Parker Pen Company, Janesville, Wis., a corporation of Wisconsin

Application August 28, 1958, Serial No. 52,436

Term of patent 14 years

(Cl. D74—1)

FIG. 3

FIG. 4

FIG. 5

Fig. 1 is a side perspective view of a desk base for a writing instrument embodying my new design, the dotted line showing of a writing instrument being for illustrative purposes only;

Fig. 2 is a side elevational view thereof;

Fig. 3 is a top plan view;

Fig. 4 is a front elevational view; and

Fig. 5 is a rear elevational view thereof.

I claim:

The ornamental design for a desk base for a writing instrument, as shown and described.
